US00D946186S

(12) **United States Design Patent** (10) **Patent No.:** **US D946,186 S**
(45) **Date of Patent:** **** Mar. 15, 2022**

(54) **FLASHLIGHT**

(71) Applicant: **Promier Products Inc.**, Peru, IL (US)

(72) Inventor: **Cody Duane Grandadam**, Peru, IL (US)

(73) Assignee: **Promier Products Inc.**, Peru, IL (US)

(**) Term: **15 Years**

(21) Appl. No.: **29/728,119**

(22) Filed: **Mar. 16, 2020**

Related U.S. Application Data

(63) Continuation of application No. 29/568,777, filed on Jun. 21, 2016, now Pat. No. Des. 878,650.

(57) **CLAIM**

I claim the ornamental design for a flashlight, as shown and described.

DESCRIPTION

FIG. 1 is a top perspective view of a flashlight according to a new design.

FIG. 2 is a front view of the flashlight shown in FIG. 1.

FIG. 3 is a rear view of the flashlight shown in FIG. 1

FIG. 4 is a right side view of the flashlight shown in FIG. 1.

FIG. 5 is a left side view of the flashlight shown in FIG. 1.

FIG. 6 is a top view of the flashlight shown in FIG. 1.

FIG. 7 is a bottom view of the flashlight shown in FIG. 1.

FIG. 8 is a top perspective view of a second embodiment of a flashlight according to a new design.

FIG. 9 is a front view of the flashlight shown in FIG. 8.

FIG. 10 is a rear view of the flashlight shown in FIG. 8

FIG. 11 is a right side view of the flashlight shown in FIG. 8.

FIG. 12 is a left side view of the flashlight shown in FIG. 8.

FIG. 13 is a top view of the flashlight shown in FIG. 8; and,

FIG. 14 is a bottom view of the flashlight shown in FIG. 8.

Those portions of the flashlight which are presented in the Figures with even spaced dotted lines (---) show the environment and form no part of the claimed portions of the flashlight. The unevenly spaced, dot-dash-dot broken lines (---) in the Figures represent unclaimed boundaries of portions of the flashlight.

1 Claim, 6 Drawing Sheets
